[57] ABSTRACT

The disclosure of this invention relates to a rail guided car adapted to be located on the operator's side of the rolling mill for engaging the adjacent end of a set of work rolls of the mill for removing and replacing the roll set relative to the mill. The car supports the rolls in a cantilever fashion and includes a counterweight which is readily and accurately adjustable to permit accurate control of the roll set when being lowered in the mill. The car also includes a linkage system for the member that engages the ends of the rolls for assuring that the rolls are maintained parallel to a desired plane even though the rolls are adjustable while carried by the car.

ROLL CHANGING DEVICE FOR A ROLLING MILL AND THE LIKE

While automatic and very rapid work roll changing devices have been provided in many recent four-high rolling mills, many mills still employ porter bars or C-hooks to remove and replace the work rolls. Usually the rolls are removed one at a time, although porter bars are in use that remove and replace the rolls in pairs.

Porter bars and C-hooks require the service of a mill crane which is not only very time consuming and prevents the crane from being used for other necessary purposes, but makes accurate guiding and positive handling of the roll or rolls impossible. This results in not only substantial delay in properly positioning the rolls in the mill and aligning the rolls with the couplings of the driving spindles, but permits the rolls to be banged about resulting in damage to the mill parts and to the rolls themselves including the back-up rolls. In order to remove the rolls from the mill they are required to be lifted from the lower back-up rolls in a very limited space and when replaced they have to be lowered onto the lower back-up roll. In the past, during this operation many times the upper back-up roll was forcefully hit by the upper work roll and the lower back-up roll with the lower work roll resulting in many cases in damage to the rolls.

Notwithstanding the disadvantages of employing C-hooks or porter bars to change the work rolls, heretofore this was the only option open to the industry other than the very expensive fully automatic arrangements, such as turntables and side-shifters, used with push or pull work roll extractors. In addition to the very large initial capital expense when attempts were made to adapt them to existing mills the automatic arrangements required substantial alteration to the mill; for example, a redesigning of the windows and bearing chocks to accommodate the extractors and the inclusion of roll supporting rails.

It is, therefore, the object of the present invention to provide a device for changing one or more rolls of a rolling mill or like device which will not require the services of a crane or alterations to the mill or device itself and which will permit accurate, positive, and relatively rapid removal and replacement of the roll thereby eliminating any possible damage to the adjacent parts, including roll damage.

It is another object of the present invention to provide a guided roll carrying car located on the operator's side of the mill for engaging the end or ends of one or more rolls of the mill for removing and replacing the roll or rolls relative thereto, said car including means on the car for cantileverly supporting the roll or rolls, and a counterweight which is readily and accurately adjustable to permit accurate control of the roll or rolls when being lowered in the mill.

A still further object of the present invention is to provide the aforesaid car with a linkage system for the means that supports the roll or rolls for assuring that the roll or rolls will be maintained parallel to a desired plane even though the roll or rolls are vertically adjustable while carried by the car.

These objects, as well as other novel features and advantages of the present invention, will be better understood when the following description of one embodiment

thereof is read along with the accompanying drawings of which:

FIG. 1A is an elevational view of a roll carrying car constructed in accordance with the present invention arranged on the operator's side of a rolling mill showing the car in its inoperative position;

FIG. 1B is a view similar to FIG. 1A, showing the car in an operative position adjacent the rolling mill;

FIG. 2 is an enlarged plan view of the car shown in FIGS. 1A and 1B;

FIG. 3 is a sectional view taken along lines 3-3 of FIG. 2; and

FIG. 4 is an end view taken on lines 4-4 of FIG. 2 of the car.

In referring first to FIG. 1A, there is shown a work roll changing car 10 being supported on a pair of spaced parallel rails 12 arranged on the operator's side of a rolling mill and which extends, as will be seen later, from a position remote from the window of the mill to a position adjacent thereto. The car engages the rails 12 by two pairs of wheels 14 and 16, the wheels 16 being driven by a chain and hydraulic gear motor drive 18. While the other important elements of the car 10 will be described later in connection with FIGS. 2, 3, and 4, sufficient at this point is to call attention to the roll carrying member 20 mounted on the front of the car 10 having two openings 22 for receiving the adjacent ends 24 of two work rolls 26 of a rolling mill for cantileverly supporting the rolls as a set during exchange of the rolls to and from the mill.

To the right of the car 10 as one views FIG. 1A supporting the set of rolls 24 is a platform 28 of a side-shifting device 30. It will be appreciated that the rolls shown in FIG. 1A represent a new set of rolls which have been set on the platform 28 in readiness for insertion into the mill after the worn roll set presently in the mill has been removed therefrom. Accordingly, the platform 28 is positioned to the left or right of the mill window so that in the position of the elements shown in FIG. 1A the car 10 is free to move over the rails 12 past the rolls 26. The side-shifter 30 will have a second platform similar to the platform 28 which will be moved independently of the platform 28 for supporting the worn roll set when brought from the mill by the car 20 and lowered onto the second platform after it has been brought into a position in front of the car once the car is moved from the mill to the position shown in FIG. 1A. One of the piston cylinder assemblies of the platforms is shown at 32 in FIG. 1A along with the pair of rails 34 on which the platform are supported and moved into and out of their position in front of the mill.

Turning now to FIG. 1B, the car 20 is illustrated in phantom in a position adjacent a four-high rolling mill 36 and having its member 20 engaging in a cantilever fashion, the adjacent ends of a set of worn work rolls 38. To accomplish this it will be noted that the rails 12 extend to a position adjacent the mill 36 so that the car can be properly positioned to remove and insert worn and new rolls respectively. The movement of the car to the location shown in FIG. 1B is not interfered with by the platform 38 or the rolls 26 because at this time and which is true of the second platform they have been moved to opposite sides of the rails 12.

Returning now to complete the description of the car 10 as more fully illustrated in FIGS. 2, 3, and 4, in order to be able to rapidly but accurately adjust the member 20 of the car 10 there is provided a counterweight 40

being trunnion mounted at its front end by a shaft 42. The shaft 42 is supported at the top of two spaced-apart pedestals 44 constructed as part of the frame 46 of the car 10.

It is to be noted that the counterweight 40 extends to the left of the shaft 42 as viewed in FIGS. 2 and 3 into parts 40a between which parts is inserted the member 20 and pivotally connected to the parts 40a by a shaft 48. The lower end of the member 20 is similarly pivotally connected to a pair of links 50 by a shaft 52. The other end of the links 50 is pivotally secured to the frame 46 by a shaft 54. The pivotal construction of the parts 40a of the counterweights and the links 50 and the fact that these parts 40a and the links 50 are equal in length with the shaft 42 and 54 being arranged in the same vertical plane presents a construction that will allow the member 20 and rolls carried thereby to be raised and lowered while maintaining the rolls parallel to the working position they assumed when they are in the mill 36.

The vertical movement of the roll carrying member 20 is accomplished by a piston cylinder assembly 56 arranged to extend between the frame 46 and the counterweight 40 at the end of the car 10 opposite the member 20. The piston cylinder assembly is single acting with a variable pressure control and arranged to lift the counterweight 40 and, hence, to lower the member 20 and rolls carried thereby.

As best shown in FIG. 4, the extent of upward movement of the counterweight 40 is controlled by a motorized jack 58 which needs to be only of a small capacity sufficient to move against the pressure of the piston cylinder assembly 56 when it is required to lower the member 20. The lower end of the rod of the jack passes through an opening in the frame 46 and to which is secured a pair of stop plates 60. The phantom showing of the stop plates 60 in FIG. 4 indicates the lower adjustment of the jack and the maximum upward range of movement of the counterweight 40. The counterweight is designed to move upwardly on operation of the piston cylinder assembly 56, hence lowering the rolls until the prepositioned stop plates 60 hit the upper part of the frame 46. When the pressure is removed from the piston cylinder assembly 56, the weight of the counterweight, which is 5 to 10 percent greater than the set of roll assemblies, will lower the counterweight and raise the rolls until the piston of the assembly 56 rests on the bottom of its cylinder or an adjustable stop, not shown. The total weight of a pair of work rolls of the type illustrated in FIG. 1 will be of the order of 40,000 lbs. The jack 58 is adjusted by a pair of hand wheels 62 arranged at the front of the counterweight 40, the hand wheels being connected to the jack through a miter gear drive 64 and a shaft 66.

In operation, and in referring to removing the worn rolls 38 from the mill 36, the car 10 will be brought to the position shown in phantom in FIG. 1B with the pressure on the piston cylinder assembly 56 and the member 20 positioned by operation of the piston cylinder assembly, and if necessary, the jack 58 to allow the openings 22 to be aligned with the ends of the rolls 38. After this, the rolls are engaged by the member 20 and the pressure in the piston cylinder assembly 56 is exhausted to raise the rolls to a position shown in FIG. 1B where the lower work roll 38 is lifted free of the lower back-up roll and the upper work roll assumes a spaced-relationship with the upper back-up roll. This spaced

relationship is permitted since the upper back-up roll has been previously raised in preparation for the work roll changing operation. The upper movement of the work rolls is controlled by the piston of the piston cylinder assembly 56 contacting the bottom of its cylinder which movement is within the space allowed in the mill so that the upper work roll will not hit against the upper back-up roll. It will be appreciated that the piston's contact with the cylinder will be very slightly represented by the amount the counterweight exceeds the weight of the rolls and the member 20.

Once cantileverly supported by the car 10, the rolls 38 will be retracted to a position where they can be lowered by the car onto the second platform of the side-shifter 30. After this the car 10 is further retracted to disengage the rolls and allow the second platform to move out from in front of the mill and the platform 28 to move in front of the mill and in front of the car 10. This will place the new set of work rolls 26 in position to be engaged and raised off the platform 28 by the member 20 of the car 10 since the rolls are supported by identical bearing chocks and there will be no difference in the location of the axes of the rolls of the worn and new set so that there will be no need to adjust the member 20. It should be noted that the set of worn and new work rolls are provided with either a nested chock construction, removable stools or built-in stools that allow the upper work roll to be supported by the lower work roll during their transit.

Once raised, the platform 28 is moved to the side of the mill opposite to the side that the second platform was moved and the car 10 carrying the new work roll set 26 in cantilever fashion is advanced to the position of FIG. 1B. In raising the rolls 26 off the platform 28, the piston cylinder assembly 56 is exhausted which condition will remain until the rolls 25 are inserted into the window of the mill 36. While in this raised position the new rolls assume the same elevation as the worn rolls when positioned for their removal from the mill so that the new rolls will be properly aligned with respect to the driving couplings of the mill for automatic insertion of the rolls into the couplings. Once in the mill 36, pressure will be introduced into the piston cylinder assembly 56 to raise the counterweight 40 and lower the rolls 26 to the extent allowed by the stop plates 60 of the jack 58. The setting of the jack will be such that the piston cylinder assembly 56 will not lower the roll enough so that the lower work roll will hit against the lower back up roll. Instead, the final lowering of the work rolls onto the back-up roll will be performed by operation of the jack 58 to raise the counterweight 40 against the pressure of the piston cylinder assembly 56 and very slowly and carefully lower the work rolls until the lower work roll is supported by the lower back-up roll. At this point the car can be retracted to its inoperative position shown in FIG. 1A.

In accordance with the provisions of the patent statutes, I have explained the principle and operation of my invention and have illustrated and described what I consider to represent the best embodiment thereof.

I claim:

1. An apparatus for removing and replacing a roll to and from a rolling mill or the like, comprising:
a car arranged on the operator's side of said mill, said car including a member at its end adjacent to the mill for cantileverly supporting a roll in a position

parallel to its working position when the roll is in said mill,
 said car including a counterweight arranged to offset at least a part of the weight of said roll when supported by said member,
 means for pivotally supporting said counterweight, linkage means for connecting said counterweight to said member in order that vertical movement of said counterweight is translated to said member,
 means for effecting said vertical movement of said counterweight comprising a piston cylinder assembly,
 means for restricting the upper movement of said counterweight comprising a mechanical jack having a stop means,
 means for mounting said mechanical jack on said

counterweight for movement therewith, and said stop means of said mechanical jack constructed and arranged for contacting with said car on said upper movement of said counterweight.
 5. 2. An apparatus according to claim 1 wherein said jack and stop means are so arranged that operation of said jack will bring about a raising of said counterweight and an accurate lowering of said member.
 3. An apparatus according to claim 1 wherein said 10 piston cylinder assembly is a single action piston cylinder assembly constructed and arranged so that its piston will limit the extent to which said counterweight is lowered and wherein the weight of said counterweight is made to exceed the weight of said member and said 15 roll.
